Primary Examiner — Rosemary K Tarcza*Assistant Examiner* — Nathaniel D Buckner(74) *Attorney, Agent, or Firm* — Gottlieb, Rackman & Reisman, PC**CLAIM**

The ornamental design for a charging device, as shown and described.

DESCRIPTION

FIG. 1 is a first perspective view of a charging device showing my new design;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a second perspective view thereof.

The broken lines shown in the drawings are included for the purpose of illustrating portions of the article that form no part of the claimed design.

1 Claim, 3 Drawing Sheets---
